UNITED STATES PATENT OFFICE.

WILLIAM NICHOLAS, OF NEW YORK, AND WILLIAM ACKERMAN, OF LARCHMONT, NEW YORK, ASSIGNORS, BY MESNE ASSIGNMENTS, TO UNITED STATES GRAPHOTYPE COMPANY, A CORPORATION OF NEW YORK.

CANCELING MEANS FOR TYPE CASTING AND COMPOSING MACHINES.

1,279,897.

Specification of Letters Patent. Patented Sept. 24, 1918.

Application filed July 7, 1914, Serial No. 849,572. Renewed August 19, 1918. Serial No. 250,606.

To all whom it may concern:

Be it known that we, WILLIAM NICHOLAS, a subject of the King of Great Britain, residing at No. 222 West Twenty-third street, 5 in the city of New York, county and State of New York, and WILLIAM ACKERMAN, a citizen of the United States, residing in the village of Larchmont, in the county of Westchester, in said State, have invented 10 new and useful Improvements in Canceling Means for Type Casting and Composing Machines, fully described and represented in the following specification and the accompanying drawings, forming a part of the 15 same.

Our invention relates to record controlled type casting and composing machines, and more particularly relates to improvements in the means whereby the usual operations 20 thereof are modified so as not to cast characters it is desired to omit from the composition.

Machines of this type have been illustrated in connection with the United States 25 patent to G. A. Goodson dated August 16th, 1898, No. 609,098, and also in Patent No. 715,233, dated December 9th, 1902, issued to W. Ackerman, co-inventor of the present improvement, it being the purpose of the present 30 invention to attain this end in a more direct and effectual manner.

While the preferred form of our mechanism illustrated herein is designed to operate in connection with a type casting machine, such as is described in our joint U. S. 35 Patent 964,677, it is not desired to limit the application of the same to that one form of machine, as with unimportant modifications it may be adapted to operate in connection with other forms of type casting machines. Nor is it essential that any particular form of controller mechanism be employed to operate the parts constituting our invention, and therefore the tape controller 40 described in our joint United States Patent 964,678 which is adapted to operate in connection with the type caster of our first mentioned joint patent may be used, or the selector controller devices described 45 in our joint Patent No. 964,679 may be employed with the same results. However, inasmuch as the present invention in its preferred form is applied to the type casting machine described in our last mentioned pat-

ent, which is a co-called one-man machine 55 and has the controller device formed of separate selective controller devices, our present invention will be more or less particularly described in connection with the mechanism therein illustrated, reference being made in 60 this connection to the parts described in said last mentioned joint patent in so far as the same may be applicable to our present purposes.

It will therefore only be necessary to point 65 out in this connection that in the use of the perforated tape controller of the type described in connection with our first mentioned patent, a slightly different order is followed in its preparation and presentation 70 to the type casting mechanism than in setting the separable controller devices or selectors of the so-called one man machine described in our said joint Patent 964,679. We will therefore briefly refer to the pertinent 75 features of the two methods, in so far as they relate to our present apparatus.

Thus, in preparing the tape the operator will by means of the proper key make a special "line cancel" perforation in the strip in 80 the space immediately following matter to be omitted, in the place of the usual justification perforation, which is immediately followed by the trip signaling perforation. When the ribbon is fed through the index 85 head in its reverse order, as is usual in machines employing the tape record presentation, the trip perforation through the electrical contacts may thereby cause the cam that constitutes the justifier parts to rotate, 90 which as one of its functions will be made to actuate the mechanism of our present invention which by operating special means presently to be explained, is adapted to render inoperative the mold plunger actuating 95 means, not only during the setting of the justifier parts, which is normally and automatically performed each time the usual trip signal controller passes through the index head, but also for the extended period covering 100 the line cancel requirements, which is effected through the action of the special "line-canceling" perforation of the tape above referred to. Such mechanism is necessary for the reason that the mold plunger 105 mechanism being actuated by the main driving shaft would cast a type at each revolution thereof, unless some means is especially

provided to prevent its operating at certain intervals. Furthermore, inasmuch as the driving shaft of the caster is carried through two rotations while the justifier cam is operating to set the justifier mechanism and perform the other functions relating thereto, it is obviously indispensable that the justifier cam should interpose preventive means to the action of the plunger mechanism while 10 said cam is performing the operation above referred to. Therefore, as the trip perforation operates to cause the justifier cam to rotate, which in the manner indicated shuts off the pump mechanism from operating, it 15 is only necessary to interpose an independently operated locking device to the mechanism thus ordinarily actuated by the justifier cam, which will retain the mold plunger in its inoperative position indefinitely, or until 20 the dead matter of the controller has been run through the index head of the machine. This separate mechanism is made necessary for the reason that the justifier cam only holds the plunger mechanism out of 25 commission during a certain portion of its revolution, which plunger mechanism would therefore be free to operate to cast type immediately upon the justifier cam coming to its normal position of rest.

30 Therefore, having interposed such independent locking device which may be termed the line-cancel latch mechanism, it is only necessary to construct such line canceling lock in a manner that will admit of its automatic release upon the succeeding revolution of the justifier cam which will necessarily be tripped at the commencement of the next succeeding line to be reproduced in type. That is to say, inasmuch as each line of 35 composition must be preceded by a trip perforation, it is apparent that the line canceling lock will not need to be released until the new line is thus introduced into the composition, which is accomplished automatically by 40 the action of the cam upon the latch mechanism.

The controller devices employed in connection with the mechanism illustrated in our said Patent 964,679, may be employed to 45 coöperate with the mechanism of our present invention, and are introduced into the index head of the casting machine, in the same general manner in which the tape perforations are employed as above described. It 50 is therefore not necessary to describe in detail in this connection the method whereby the justifier selector is introduced into the procession of selectors at the position next following the trip selector at the head of 55 those representing a given line, it being apparent that the trip selector in the practice of our present invention will be followed immediately by a line cancel selector which will have its selective collar located by the mechanism described in said patent at a position 60

to operate the actuating mechanism that controls the line canceling locking device, which in the preferred form of our present invention comprises as one of its essential features an electromagnet which is energized 70 by action of a circuit closing device corresponding with the line cancel perforation or selector as the case may be.

Therefore, generically our improvement includes in its complete form means for setting a controller device to operate a specially provided electromagnet which in turn will interpose a stop or latch mechanism in the path of the slide which operates the mold plunger, thereby preventing the casting of the type until such latching is subsequently released. It will therefore be necessary in describing our invention in detail to include certain portions of the mechanism described in the above patents, which 80 incidentally are incorporated in the mechanism of our invention, it being apparent, however, that several equivalent mechanisms can be used for the same purposes.

Where our invention is employed in connection with tape operated machines, or those of the one man type in which separable controller selectors constitute the presentation record, the trip signal device in which ever form employed will be followed immediately by a specially prepared signal device which will operate the line canceling mechanism of our invention, thus occupying the position normally assigned to the justification perforation or selector as the case 90 may be.

Heretofore, in connection with casting and composing machines, especially the electrically controlled class thereof, it has been the practice to have an electrically operated mechanism to engage the connecting rod which causes the pump plunger to operate to cast a type at each rotation of the cam driving shaft, so as to throw that member out of engagement with its respective actuating cam, thereby rendering the pump plunger inoperative during the rotation of the justifier cam while that member is setting the justifier mechanism, at which time of course no type will be cast. In our present invention we have devised mechanism whereby the justifier cam drum, by action of specially designed cam surfaces thereon, will automatically interpose a locking arrangement in the path of the pump rod so as to hold that 100 member out of alinement with the pump operating cam on the main shaft of the casting machine, during the entire rotation of the justifier drum.

Hence, our invention broadly described 125 attains the object of the line cancellation by adding a mechanism whereby the locking device which is operated by a cam on the justifier drum to scotch the pump rod, may be held out of action indefinitely or until it 130

is desired to begin casting a new line. In that case, the special locking device of the line cancelling mechanism will be automatically released by action of the cam on 5 the justifier drum so as to release the line canceling lock.

In the accompanying drawings, illustrative of a preferred embodiment of our improvement, Figure 1 is a plan view of a part 10 of a casting mechanism showing a portion of the driving shaft of the type casting mechanism with the justifier cam and mold plunger rod. Fig. 2 is a sectional side elevation of parts shown in Fig. 1, showing the 15 line canceling locking device in position to be thrown into engagement.

Referring to the drawings: 1 represents the frame of a type casting machine of the class to which our invention applies, having 20 a bed plate 2, and a top plate 3 immediately above the bed plate, and a main shaft 4 which is supported by means not shown, upon the framework of the machine. Upon the shaft 4 are the several actuating cams of 25 the casting machine, only two of which are illustrated in the drawings in connection with our present invention, namely the cam 8 which relates to the pump operating mechanism and the drum 15 upon which are the 30 various cams employed in connection with the setting of the justifier parts, which will be referred to as the justifier cam, having added thereon a special cam 16 suitably arranged and timed to interpose a latch to lock 35 the pump rod 5 from engagement with its cam 8. The justifier cam is loosely mounted upon a sleeve upon the cam shaft 4, which sleeve is a part of the mechanism by means of which the cam 15 is intermittently 40 clutched to the cam shaft 4 through the action of a trip mechanism, fully described in connection with our said joint Patent No. 964,697, it being sufficient to point out in this connection that whenever the trip is 45 operated by means of which an operable connection is effected between the shaft 4 and the cam 15, whereupon the latter makes one revolution while the shaft is passing through two complete rotations.

50 Slidably mounted upon the top plate 3 is the pump rod 5 which is operably connected at one end with the pump plunger of the type casting machine and is carried by spring action in the direction of the cam 8 on 55 the driving shaft, in order to operate said plunger to force the molten metal into the mold for casting type. Upon the opposite end of the slide 5 is a cam roll 7 which by the spring action above referred to, is oper- 60 ably held in contact with the periphery of the cam 8, in which is a depression 9 into which the cam roll 7 is thereby thrust when that portion of the cam is carried into the proper position to operate the mold, the rear- 65 most side of said cam depression being

adapted by a gradual incline to return the slide 5 in its normal position with the roll upon the periphery thereof, as the cam 8 continues its rotation. In this manner the pump is worked by the spring actuated 70 pump rod 5 to cast a type with each rotation of the driving shaft, unless held out of engagement with its cam by other means which it is the purpose of our invention to provide and will now be described. 75

A hook lever 10 that has heretofore been employed to act as a safety lock on the pump rod 5 is pivotally mounted upon a bracket extending upwardly from the top plate 3 and has its hooked end 11 adapted to engage corresponding toothed projection 6 upon the pump rod slide 5 while the roll 7 rests upon the periphery of the cam 8. The hooked lever 10 is therefore carried downwardly upon its pivotal bearing in order to be thrown into a position to hold the slide 5 in the manner indicated, from dropping into the depression 9 for the purpose of casting type. 80

The hooked lever 10 is held normally in locking position by spring yielding means 6', urging the hooked portion 11 into engagement with the toothed member 6 so that it requires releasing means in order to permit type to be cast. To this end the opposite end of the hooked lever 10 has an arm 12 which has a loosely pivoted finger 13 attached at the extreme end thereof and suitably held in a normally upright position by link connection with the frame of the machine so as to be contacted by the under side of the matrix frame A which is hinged to the top portion of the machine, and when type are to be cast thereby is brought down into position contacting the member 13 and lifting the latch 11 at the opposite end of the hooked lever 10; so that at the succeeding revolutions of the pump actuating cam 8, unless otherwise held out of engagement therewith, the roll of the pump rod will drop into the notch 9 of the pump cam and the plunger thereby operated to cast the type. Inasmuch, however, as it is necessary to effect the line canceling omission in the casting operation of the machine while the matrix frame A is in position to cast, it is found desirable to throw the latch 11 into engagement with the tooth of the slide 5 while the matrix frame is in position to normally hold the latch 11 out of engagement therewith. 90 95 100 105 110

Consequently the finger 13 is made in two parts yieldably connected one to the other by means of a compression spring 14 supported upon a rod 14^a so that as the matrix frame at A presses upon the top of the finger 13 it actuates the hooked lever 10 through yielding means to withdraw it from engagement with the tooth 6 so that the pump rod may be carried by its spring to operate the pump when permitted so to do by the cam 115 120 125 130

8, as described. Hence, while the hooked member is thus being held out of engagement with the slide 5 to permit the pump plunger to act, other means must be employed 5 to depress the hooked end of the lever 10 into engagement with the tooth of the pump controlling slide 5 when it is desired to prevent the casting of the type while the machine is in operable condition otherwise. 10 Such result is accomplished in the present invention by means of cam block 20 on the hooked lever 10 upon the top portion of which is the upwardly inclined cam surface 21, upon which bears a pin 23 projecting 15 laterally from the swinging arm 22 that is suspended immediately above the block 20. As the arm 22 is rocked to the right as shown in Fig. 2, the pin depresses the cam block, the surface 21 of which is there shown 20 in its normal unlocked position, in the path of the pin 23 on said arm. The arm 22 is pinned to a rock shaft 24 suitably supported in a bracket 24^a upon the top plate 3 and is actuated by means of a 25 lever arm 25 which is secured to said shaft 24 by means of the set screw 25^a. At the free end of the arm 25 is a stud 26 and loosely mounted thereon is a cam roll 27 which is held, by action of the torsion spring 30 28 on the rock shaft 24, in yielding contact against the periphery of a cam 16 secured to the justifier cam drum 15. The cam 16 is so designed that when the roll of the arm 25 is resting upon the low portion thereof 35 as best shown in Fig. 2, the pin of the swinging arm 22 is carried out of engagement with the inclined portion of the cam surface 21 of the block on the latching lever 10 having a raised portion thereon so designed that 40 when the roll 27 rests thereon, the pin 23 will have been forced along the surface 21 with the result that the latching lever 10 is thrown into engagement with the tooth projection 6 of the pump slide, thereby locking 45 it so as to forestall the casting operation. The high part of the cam 16 is sufficiently prolonged so that it is in contact with the cam roll to lock the pump throughout the major part of the rotation of the justifier 50 cam covering all the setting operations thereof, during which period the pump is locked in the manner indicated. The cam however coming to its normal position of rest as shown in Fig. 1, with the swinging 55 arm 22 brought into the low part of the cam surface of the block 20, permits the latch 11 to be carried out of locking engagement with the pump plunger mechanism. Thus is attained the purpose of omitting the casting 60 operations during the circuit setting process when no type are to be cast, it being necessary so to lock the pump mechanism for the reason that the main driving shaft has rotated twice during the revolution of the 65 justifier cam, and but for the action of the

locking mechanism at each revolution a type would have been cast, which would of course not be permissible.

While the mechanism as thus far explained would be adequate in forestalling the casting operations during the period occupied by the setting of the justifier mechanism, it will be apparent that if the period of eliminating type casting should be required to extend beyond the mere setting 70 operation other mechanism will be required. Therefore, when a number of characters or an entire line is desired not to be cast, *i.e.*, to be canceled, instead of inserting a justification controller signal immediately after the 75 trip signal in the usual way, a special line cancel selector or perforation is introduced at that point in the controller, which in our present form of mechanism when introduced into the index head, is designed to close an 80 electric circuit in which is included an electromagnet 35 which is provided with means for holding the swinging arm 22 indefinitely in a locking position with reference to the cam block 20 on the hook lever 11. 85

The means by which the magnet 35 accomplishes this locking purpose comprises a lever armature 36 pivotally supported upon a post 37 being held normally out of contact with the magnet 35 by means of the spiral spring 38 secured to one side of the lever 36 at one end, secured at the opposite end to a pin suitably projecting from the post 37. The armature lever at its opposite end is adapted to engage the bottom 90 of a latch 40 which is slidably mounted in a suitable bearing vertically disposed in the bed plate 3, upon the upper end of which is the toothed portion 41 adapted to engage a correspondingly hooked end 46 of a horizontal latch member 45 which is also slidably mounted in a bracket block 47 and adapted to slide in a path immediately above the position of the locking slide 40, and when the latter is held in its normal inoperative position shown in Fig. 1, to pass freely 95 over the head thereof. The vertically sliding latch member 40 is held in its normally disengaging position by means of a coil spring 42 upon the stem thereof, there being provided for the purpose a collar 43 suitably secured to the end thereof, the other end of the spring bearing against the under side of the plate 3 in which the slide 40 has its bearing. The horizontal sliding 100 latch member 45 is connected by a short pitman 48 which is pivotally mounted with the latch member 45 at one end being attached at its other end to the stud 26 upon the actuating arm 25 by means of which the 105 hooked arm 11 is operated. 110

Consequently, as the cam 16 rotates from the position shown in Fig. 1 it forces the arms 22 and 25 outwardly, thereby performing two distinct functions, namely, pressing 115

the hooked lever 11 into locking engagement with the pump rod, and at the same time carrying the horizontal sliding member 45 into a position so that if the magnet 35 be 5 energized the armature lever 36 will be carried against its spring 38 to force the vertical latch slide 40 upwardly into engagement with the slide 45, so that as the cam 16 coming to its position of rest recedes from 10 the roll the slide 45 starts to return with it, but will now be held by the latch member 40 in the position to which the cam 30 has carried it in which position, as has been seen, the cam of the hooked member 11 is 15 held to lock the pump rod. Thereupon the cam 30 remaining in the position in which it presents the low portion thereof to the slide 45, that member is only held by the latch 40, which is held in such position 20 against the action of its spring 42. The armature lever having immediately returned to its normal position of rest, the parts will therefore remain in this locking position with reference to the pump rod until the 25 justifier cam through the action of a new trip selector signal is caused to make another revolution at which time the cam 16 as its high part strikes the roll will move the horizontal latch slide 45 just enough to 30 release the vertical latch 40 which by action of its spring will be carried out of engagement therewith to allow the arm to fall back as the cam 16 rotates, thereby throwing the swinging arm to release the hooked 35 lever 11 from locking engagement with the pump rod. The pump controlling mechanism will therefore again be in commission, so to remain until the justifier cam interferes, or until the magnet 35 is again energized 40 by a new line canceling impulse from a new line cancel selector signal, and the machine will resume its ordinary operation. Hence, the justifier cam 15 by action of the cam 16 therewith not only forestalls the action 45 of the pump rod during the circuit setting operation, but also during the action of the working circuits for an indefinite number of rotations of the driving shaft or until such time as it is desired to start in 50 with a new line of composition.

Having described our invention, what we claim is:

1. In a type casting and composing machine provided with record control, means 55 for cutting out the pump operating mecha-

nism by action of a specially prepared signal in the record control thereof; and an electro-magnet actuated thereby to lock said cutting out means.

2. In a type casting and composing machine, a record control; means for cutting out the pump operating mechanism; and an electro-magnet controlled by a signal in a record control to lock said cutting out means; said lock comprising means for automatically releasing the said locking means by action of the normal record control device.

3. In a type casting and composing machine, record control devices; means comprising a trip controller for normally cutting out the pump mechanism during the initial revolutions of the driving shaft thereof; and means for retaining indefinitely said pump cut-out mechanism in a locking 75 position controlled by a special line cancel controller device.

4. In a type casting and composing machine, record control devices; means comprising a trip controller for normally cutting out the pump mechanism during the initial revolutions of the driving shaft thereof; means for retaining indefinitely said pump cut out mechanism in said locking position controlled by a special line 85 cancel controller device; said trip controller restoring the normal operations of said pump actuating mechanism.

5. In a type casting and composing machine, record control devices; means comprising a trip controller for normally cutting out the pump mechanism during the initial revolutions of the driving shaft thereof; means for retaining indefinitely said pump cut out mechanism in said locking 90 position under the control of a special line cancel controller device; and means comprising another lock operably connected with an electro-magnet to hold said pump locking mechanism indefinitely in an inoperative 95 position; and means for releasing said pump locking mechanisms.

In testimony whereof, we have hereunto set our hands in the presence of two subscribing witnesses.

WILLIAM NICHOLAS.
WILLIAM ACKERMAN.
